CLAIM

The ornamental design for a scent dispenser, as shown and described.

DESCRIPTION

FIG. 1 is a front perspective view of a design for a scent dispenser;

FIG. 2 is a front view thereof;

FIG. 3 is a rear view thereof;

FIG. 4 is a left side view thereof;

FIG. 5 is a right view thereof;

FIG. 6 is a top view thereof; and,

FIG. 7 is a bottom view thereof.

The broken lines shown in the figures are for the purpose of illustrating portions of the scent dispenser and form no part of the claimed design.

1 Claim, 6 Drawing Sheets
